PORTABLE BEACH APPARATUS

Amos E. Heath, Washington, D. C.

Application December 19, 1931
Serial No. 582,132

6 Claims. (Cl. 254—166)

The present invention relates to life saving equipment and more particularly to a motor propelled beach apparatus capable of carrying to a beach or shore at a point abreast of a stranded vessel, suitable equipment for effecting communication between the vessel and the shore in order to save the lives of those upon such vessel in distress.

Among the several principal appliances for saving life from a shipwreck as employed by the Life Saving Service of the United States Coast Guard, is the surf boat, but when it is impractical to use such a boat, wreck ordnance is relied upon for establishing communication with the stranded vessel and this ordnance equipment comprises usually, a gun capable of firing a projectile to which is attached a shot line, so that when the gun is fired, this shot line is played out until it passes over the vessel in distress. The crew of the vessel, after catching the shot line, attach thereto a whip line which latter consists of an endless rope rove through a tail block, the latter being made fast to a mast of the vessel. This whip line is then brought to the shore by the beach crew who, in turn, fasten the whip line over a block pulley suitably fastened to a post positioned upon the shore or anchored in any manner to a stationary object upon the shore. By means of this whip line, communication is established between the shore and the stranded vessel, or vice versa. A hawser line is then attached to the whip line, usually by the life saving crew upon the beach and this hawser line is drawn taut between a stationary object upon the beach and the vessel, preferably at about two feet above the whip line. A breeches buoy block is usually snapped upon the hawser and the breeches buoy carried by the same is hauled to and from the wrecked ship by the whip line. A carriage or apparatus cart containing this equipment is usually dragged to the scene of the wreck by draft animals, and in order to facilitate and hasten the transportation of the equipment to the scene of the wreck, I preferably use a motor propelled truck, capable of traveling over the improved highways or over unimproved roads or sandy beaches. Manual labor has heretofore been employed for hauling the shot, whip and hawser lines between the stranded vessel and the beach, which not only takes up considerable time, but, owing to the fact that ice forms upon these ropes or lines, it is difficult for the same to be handled by the beach crew, and therefore, it is the purpose of the present invention to provide a motor propelled truck not only capable of

transporting the life saving equipment, but having suitable winding and reeling mechanism mounted thereupon propelled by the power plant of the truck in order that the ropes employed in the lines of communication between the stranded vessel and the shore may be hauled in under mechanical power, thereby saving considerable time, which is of vital interest in the saving of life from a shipwrecked vessel.

Another equally important object of the invention is to provide a combined power driven winch and reeling apparatus capable of being easily and readily installed upon a standard motor truck, requiring but a comparatively limited amount of space and which, when installed, will take care of or wind up several ropes or lines as they are hauled in in an efficient and systematic manner in order that the ropes may again be payed out as required.

Other objects of the invention will be in part obvious and in part pointed out hereinafter.

In order that the invention and its mode of operation may be readily understood by persons skilled in the art I have in the accompanying illustrative drawings and in the detailed following description based thereon, set out several possible embodiments of the same.

In these drawings:—

Figure 1 is a vertical transverse section through a motor truck frame and chassis showing, as applied thereto and in front elevation, one form of my invention;

Figure 2 is a detail longitudinal section through the body of the motor truck taken on the line 2—2 of Figure 1 in the direction of the arrow 90 points;

Figure 3 is a view similar to Figure 1, showing a slight modification, to wit, a power take-off between the winch and one of the reels;

Figure 4 is another view similar to Figure 1 showing a further modification wherein the reels embodying the present invention are power driven, and

Figure 5 is a detail section through the body of the motor truck showing the center supporting standard for the reels.

Referring now more particularly to the accompanying drawings wherein like corresponding parts are designated by similar reference characters throughout the several views, I have herein shown a portion of a motor driven truck chassis comprising channelled side beams 1, upon which is mounted the body of the truck comprising the floor 2, side panels 3, a forward panel 4 and a cab 5. This body is of the open type in order

that life saving equipment may be stored therein and readily transported, and the cab 5 is positioned at the forward end of the truck body.

The motor truck is provided with the usual transmission housing 6 and a housing 7 arranged at the side thereof in which the power take-off is enclosed. This power take-off is provided with a drive shaft 8 which, at times, may be connected through the transmission gearing arranged within the housing 6 to the power plant of the motor truck, whereby power may be transmitted to this drive shaft 8. Suspended from the channeled side beams or bars 1 are the brackets 9 carrying an L-beam 10 upon the latter of which is supported a bearing 11 and journaled within this bearing 11 is one end of the driven shaft 8. Secured to the outer extremity of this drive shaft 8 is a sprocket wheel 12 over which passes a sprocket chain 13.

Supported within the body of the truck in back of the cab 5 thereof is a frame having supported thereon, a winch of any preferred or well known construction now commonly used, and immediately arranged above this winch are the rope winding reels A and B. This support for the combined winch and reels comprises a base being formed from a pair of parallel L-beams 14 which are connected together by suitable cross beams 15. This base is suitably secured to the bottom 2 of the truck body and supports a gear housing 16 as well as the bearing 17. This gear housing is provided with suitable gearing whereby power may be transferred from the drive shaft 8 to the shaft of a drum 18. In order to effect this connection, a sprocket wheel 19 extends to one side of the gear housing 16, over which passes the sprocket chain 13 whereby with rotation of the drive shaft 8, the sprocket wheel 19 will also be rotated therewith in order that the drum 18 of the winch may be caused to be rotated. At this point, it is to be understood that through the take-off connection and gearing shown, the drive shaft 8 may be driven in opposite directions or at various speeds, and according to the direction or speed of rotation of the drive shaft 8, the sprocket 12 will be carried therewith. Whereas one end of the shaft for the drum 18 is journaled within this gear casing 16, its opposite end is connected through a clutch 20 to a shaft journaled within the bearing 17 and secured to this latter shaft is a niggerhead 21. A hand lever 22 is provided and has connection with the clutch 20 whereby the niggerhead 21 may be at times operatively connected to the drum 18 in order that it may rotate therewith. This lever also carries a brake shoe 23 which is adapted to engage the flange 24 of the drum 18 for controlling the latter when it is free as in the case of paying off rope wound thereupon. That end of the drum of the shaft 18 which is journaled within the gear casing 16 may extend to one side of the latter in order that through a flexible coupling 25 it may be connected to a shaft 27 carrying another niggerhead 26. This shaft 27 is journaled within a bearing 28 mounted upon the base frame and extends through one of the side panels 3 of the truck body so that the niggerhead 26 will be suspended at one side of the latter.

Arranged directly above the winch are the shot whip or hawser line reels, and in order to support these reels, I provide a pair of end standards 29 each having its lower end bolted as at 30 to the side bars 14 of the base frame which supports the winch. These standards are each provided with an intermediate cross member 31 and

connecting these cross members 31 is a bar or rod 31' for further bracing the reel frame. The upper end of each standard is provided with a bearing of the split type, indicated by the numeral 32. Each split bearing comprises a lower stationary section and an upper section 33 which latter is hinged at 34 to the lower section, and the free end of each section 33 is provided with a cam and link clamp 35 for detachably connecting the same to the lower stationary section of the bearing, whereby when the hinged sections 33 of the bearings are released, easy removal of the reels may be effected. The reel frame also consists of an intermediate standard 36 which has its lower end bolted as at 37 to one of the cross bars 14 of the base frame for the winch, and its upper end is provided with an open bearing 38. A rod 39 has one end hingedly connected adjacent the upper end of the intermediate standard 36 and its lower end is adjustably connected through the bracket 40 to a strap 41 which latter is secured to the body of the truck. Two interchangeable reels A and B are provided, each comprising a shaft 42 and these shafts are provided with extensions, one of which is adapted to be seated within the opened bearing 38 whereas the opposite extensions of these shafts are journaled within the bearings 32 provided at the upper ends of the standards 29. The outer extension of each shaft of the reels is provided with a squared extremity to which may be attached a crank handle 43 whereby these reels may be manually rotated. Each reel has secured to the shaft 42 thereof, two end flanges or disks 44 and one of these reels may be provided with an intermediate flange or disk 45 which latter is also secured to the shaft 42 of that reel. These reels may be made of wood, brass, aluminum, or any other material as required or as preference may dictate.

By mounting my combined winch and reeling apparatus upon a motor truck and establishing a drive connection between the winch and the power plant of the truck, a line may be wound upon the drum 18, or by taking a couple of loops of a line about either one of the niggerheads 21 or 26, such a line may be hauled in and the excess line which has been drawn in by this winch, or the niggerheads thereof, may be manually wound upon either one of the reels A or B.

When using my apparatus in connection with life saving equipment, it at times becomes desirable to have a power take-off for one of the reels, and accordingly, in Figure 3 of the drawings, I have shown a slight modification of the invention. In this modification, as shown in Figure 3, I employ a clutch 46 which is adapted to be controlled by a hand lever 47, whereupon the drum shaft 48 may be operatively connected to the shaft 27 so that when this clutch is engaged, the niggerhead 26 may be caused to rotate with the drum shaft 48. This shaft 27 is provided with a sprocket wheel over which passes a sprocket chain 49 and the latter also passes over a sprocket wheel keyed to the shaft 50 of the reel A, whereby when the niggerhead 26 is brought into use and a line hauled in, the excess rope or line may be mechanically wound upon the reel A.

In Figure 4 of the drawings, I have shown a still further modification of the invention wherein both of the reels A and B may be power driven and when using this modification of the invention, a second power take-off comprising a sprocket wheel 51 is operatively connected to the 145

transmission gearing arranged within the housing 6. A counter shaft 52 is journaled in suitable bearings at 53 which latter are supported upon the base frame of the winch, and this shaft 52 has keyed to one end thereof, a sprocket wheel over which passes a sprocket chain 54 whereby when the sprocket wheel 51 which is connected to the transmission gearing, is set in motion, the counter shaft 52 will be caused to revolve therewith. Loosely mounted upon the counter shaft 52 are sprocket wheels 54 and each sprocket wheel 54 carries one member of a clutch, whereas the other member of each clutch is keyed to but slidably mounted upon the shaft 52 and controllable through the hand levers 55 in order that the sprocket wheels may, at times, be connected to the driven counter shaft 52 and be caused to revolve therewith. The shaft 56 of each reel is provided with a sprocket wheel 57 and adapted to pass over these sprocket wheels 54 and 57 are the sprocket chains 58 in order that when the sprocket wheels 54 are operatively connected to the shaft 52, the reels will be caused to turn therewith, whereby the excess rope or line drawn in by the niggerheads 21 or 26 may be wound upon these reels.

By employing my combined winch and reeling apparatus upon a motor propelled truck in the manner aforesaid, it is quite obvious that ample room is left within the body of the truck to carry other beach equipment, such as a gun, breecher buoy, hawser and whip lines to the scene of a shipwrecked vessel. The life saving crew, upon firing the gun from the beach or scene of the shipwrecked vessel, cause the shot line to be carried to such vessel, whereupon the sailors or crew of the vessel will attach to the light shot line, a whip line. The shot line may be connected to the drum 18 of the winch, and by setting the latter into motion, this shot line may be wound thereupon and the whip line drawn into shore. This whip line, after it is received by the life saving crew, may be connected to the niggerhead 21 by taking a couple of turns about such niggerhead, the whip line may be hauled in and the excess rope of the whip line may be wound upon the reel B comprising two sections, either by manually turning the same through one of the crank handles 43 or driving this reel through the motor of the vehicle by connecting the same through the clutch mechanism as is shown in Figure 4 of the drawings. After the whip line has been properly anchored ashore, a hawser is connected to this whip line and when this hawser is received by the life saving crew upon the shore, it may be drawn in by connecting the same to the niggerhead 26 and the excess rope of the hawser line may be wound upon the reel A shown to the right of Figure 1, by turning its crank 43 or by employing power driven means, as is shown in either Figures 3 or 4 of the drawings. After the hawser line has been drawn taut, a breecher buoy block may be clamped thereupon and the whip line connected to the breecher buoy whereby this buoy may travel upon the hawser line and be propelled back and forth between the ship and the shore.

By employing my combined winch and reel apparatus it is quite obvious that communication and transportation between the shore and a wrecked ship may be more easily and readily established and when so established the transportation of the passengers and crews from the ship may be effected in a much shorter time than that required by the equipment now in general use, as

well as materially reducing the labor necessary for handling the various ropes or lines used.

Manifestly, the construction herein shown is capable of considerable modification and such modifications as come within the scope of my claims, I consider within the spirit of my invention.

What I claim is:

1. The combination with a motor truck, having a body and a driven shaft, of a combined hauling and reeling apparatus comprising a base supported within the body of the motor truck, a winch mounted upon said base, means for operatively connecting said winch with the driven shaft of the motor truck whereby said winch may at times be caused to rotate, supports mounted upon and carried by said base, bearings carried by said support and arranged above said winch, and reels removably journaled within said bearings.

2. The combination with a motor truck having a body and a driven shaft, of a combined hauling and reeling apparatus comprising a base, said base consisting of side and end members, a winch secured to and supported by the side members of said base, a pair of end standards secured to and supported by the opposite ends of said base, an intermediate standard secured to and supported by said base, bearings supported by the upper ends of said standards, and reels removably journaled within said bearings.

3. The combination with a motor truck having a body and a driven shaft, of a combined hauling and reeling apparatus comprising a base, said base consisting of end and side members, means for mounting said base within the body of the motor truck, a winch secured to and mounted upon said base, means for operatively connecting said winch with the driven shaft of the motor truck, a pair of end standards secured to said base, bearings carried by the upper ends of said standards, reels journaled within and supported by said bearings, and means for operatively connecting said winch with said reels.

4. A portable beach apparatus comprising in combination a motor truck having a body and a driven shaft, of a support arranged within the body of the motor truck, a winch secured to and mounted upon said support, means for operatively connecting said winch to the drive shaft of the motor truck, a pair of end standards secured to and mounted upon said support, an intermediate standard secured to said support, bracing means for connecting said intermediate standard to the body of the truck, bracing means for connecting said end standards, a bearing carried by each of said standards, reels removably journaled within and supported by said bearings, and means for operatively connecting said reels with the drive shaft of the motor truck.

5. A portable beach apparatus comprising in combination a motor truck having a body and a driven shaft, a frame mounted within the body of said motor truck, said frame comprising a base consisting of side and end bars, a winch secured to and supported by said side bars and operatively connected to the drive shaft of the motor truck, end standards secured to said side members, an intermediate standard, bearings of the split type mounted upon said end standard, a bearing of the open type carried by said intermediate standard, interchangeable reels, stub shafts formed with each reel and removably journaled within said bearings, and means for operatively connecting

ing said reels with the driven shaft of the motor truck.

6. A reeling device for motor driven trucks comprising a base, said base consisting of side and end angle bars, a pair of standards each having one end secured to and supported upon one end of said base, bearings carried by the upper ends of said standards, a rod connecting the medial portions of said standards, an intermediate stand-

ard having one end secured to one of said side bars of said base, an opened end bearing arranged upon the opposite end of said intermediate standard, interchangeable reels, shafts projecting from the opposite ends of said reels and said projecting shafts being removably supported within said bearings without dismantling the latter.
